PIVOTED INNER JAW WRENCH

Gilbert L. Watson, II, Chestertown, Md.

Application April 9, 1947, Serial No. 740,319

3 Claims. (Cl. 81—97)

1

My invention relates to improvements in wrenches and more particularly to wrenches of the open-end type adapted for use with articles or members of hexagonal shape such as nuts and bolts or the like so that when any one facet of the object comes into alignment with any gripping face of the wrench, all faces will align themselves.

One of the principal objects of my invention is to provide a wrench of this type having a plurality of flat gripping faces or facets adapted to automatically snugly receive and positively grip a corresponding number of facets or faces of the hexagonal article to be gripped and rotated, in one direction, while permitting free ratcheting or rotation of the wrench, about the work, in a reverse direction.

A further object of my invention is to provide a wrench of the particular type described having an increased number of flat gripping faces for gripping the correspondingly shaped faces of the nut or bolt, and thereby reducing the tendency to burr or distort the work engaged.

A still further object of my invention is to provide a wrench of the open-end type having a fixed jaw portion with a plurality of flat gripping faces for gripping the upper and two side faces of hexagonal objects, and a sliding member manually adjustable toward and away from the fixed jaw portion and supporting a movable jaw piece having gripping faces for gripping the bottom and one side face of the hexagonal work piece, the movable jaw piece having a ratchet portion normally spring pressed into engagement with a corresponding ratchet portion on the sliding member, there being means for adjusting the tension of the spring, and the arrangement of the parts being such that the work piece will be positively gripped and rotated when the wrench is moved in one direction and the wrench will automatically ratchet around the work when moved in a reverse direction.

Other objects and advantages will be apparent as the description is considered in connection with the accompanying drawing, in which:

Figure 1 is a side view of the wrench showing in full lines the movable jaw supporting member and the movable jaw in position for gripping a hexagonal object of maximum size and in dotted lines in position for gripping an object of minimum size;

Figure 2 is a front edge view of Figure 1; and

Figure 3 is a view showing the reverse side of the wrench to that shown in Figure 1 with the parts disassembled.

2

Figure 4 is a section taken on line 4—4 of Figure 2;

Figure 5 is a section taken on line 5—5 of Figure 4;

Figure 6 is a section taken on line 6—6 of Figure 4;

Figure 7 is a section taken on line 7—7 of Figure 4;

Figure 8 is a detail view partly in section of the supporting member for the movable jaw; and

Figure 9 is a detail view of the hexagonal nut or bolt which the wrench is adapted to grip.

Referring more particularly to the drawings my improved wrench is shown as comprising a body portion 1 terminating at its outer end in a fixed jaw or curved head portion 2, and at its inner end in a straight handle portion 3. The inner surface of the curved head portion 2 is formed with two coacting flat jaw faces 4—4' arranged at an angle of 60° to each other so that they will conform exactly to two side facets 5—5' of any hexagonal object such as a nut 6 or a bolt, not shown. A third jaw face 7, also formed on the inner surface of the head or fixed jaw portion 2 and connecting the jaw faces 4—4' at their upper ends, is so placed as to be exactly parallel to the upper facet 8 of the nut 6, when the jaw faces 4—4' of the wrench are in engagement with the facets 5—5' of the nut.

The inner edge or surface 9 of the body portion 1 of the wrench is provided, as shown, with a longitudinally extending recess 10, adapted to snugly but slidably receive therein a member 11, which in turn supports a movable jaw 12 for longitudinal sliding movement therewith toward and away from the jaw head 2. The supporting member 11 has a straight rear edge or face 13, which is maintained in snug engagement with the inner or bottom wall 14 of the recess 10, while the front or forward edge or face 15 of member 11 is formed with a shoulder 16 for a purpose presently described.

Projecting from the lower end of member 11 is an integral threaded stem like portion 17, which passes through and is threadedly engaged by a milled circular nut 18, the latter being loosely received in a cross slot 19 formed in the body portion 1, at right angles to and communicating with the recess 10. Manipulation of the nut 18, in an appropriate direction, enables the user to adjust the member 11 together with the jaw piece 12, carried thereby, to their initial operative positions, for engagement with hexagonal work pieces of varying sizes. The straight rear edge 13 of jaw supporting member 11, is maintained

in snug slidable contact with the bottom wall 14 of recess 10 by the action of a pair of links 20-20', pivotally connected at their inner ends by a pin 21, which also passes loosely through registering slots 22-22' formed in the side walls 23-23' of recess 10. The outer ends of the links 20-20' are pivoted to the movable jaw member 12 by means of pins 24-24' which seat pivotally in the opposite ends of a transverse opening or bearing 25, extending through the member 12. It will also be noted that the movable jaw supporting member 11 is cut back to form the forward flat inclined edge portion 15 and the shoulder 16, previously mentioned. This flat edge 15 is provided with ratchet teeth 26, intermediate its length, which coat with corresponding ratchet teeth 27 formed on and intermediate the length of the flat rear edge portion 28 of the movable jaw 12. When the ratchet teeth are in mesh the coacting opposing flat edge portions 15 and 28 of the parts 11 and 12 also snugly engage each other. The shoulder 16 is provided with a threaded circular opening 29 which accommodates a set screw 29'. A coil spring 30 seats at its lower end in the threaded opening 29 against the set screw 29', and at its upper end this spring bears resiliently against the bottom edge 31 of the jaw 12, and normally urges the movable jaw upwardly relative to the supporting member 11, a small pin 32 being employed to prevent accidental disengagement of the movable jaw and the upper end of the coil spring. While the link 20-20' and coil spring 30 are constructed to maintain the ratchet teeth 26 in exact mesh with the teeth 27, during the working stroke of the wrench, as shown in Figure 1, the movable jaw 12, can be caused to swing downwardly and outwardly about pivots 21, 24-24' for disengaging the ratchet teeth and permitting free reverse wrench movement about the nut 6. The pressure exerted by the spring 30 can thus be increased or decreased by screwing or unscrewing the set screw 29' with a suitable tool, not shown, such as a screw driver.

The faces of the ratchet teeth 26 on member 11, are exactly parallel to the corresponding faces of the teeth 27 of the movable jaw 12, and the respective teeth are maintained in perfect mesh with each other by the expansive action of coil spring 30. Manual initial adjustment of the wrench opening 37, in either direction, to exactly accommodate a hexagonal object of a given size, is effected by turning the milled nut 18 in a suitable direction. The movable jaw can be pulled downwardly manually against the tension of the spring 30 to admit the work through the opening 37, or this can be accomplished by manipulation of the jaw face 34 against the work, or the wrench can be placed over work from a thread-axial position, that is, from either side. When the pressure against spring 30 is relieved the latter will automatically move ratchet teeth 27 into mesh with teeth 26, and move work and wrench facets into precise alignment.

Movable jaw 12 is formed with a gripping face 33, identical in dimensions to faces 4-4' of the head or fixed jaw portion 2, and a portion of a second gripping face 34. These faces 33 and 34, which are disposed with respect to each other at an angle of 120°, receive two of the six facets of the nut or bolt 6 being gripped by the fixed head or jaw portion 1, for example, facets 35 and 36. As previously stated, downward movement of the movable jaw against the tension of spring 30, incident to the initial placing of the wrench

with respect to the object can be effected manually by manipulation against the object. When the work has thus been forced through the wrench opening 37 and into operative position, 5 relative to the object 6, the handle 3 is moved to the left or in an anti-clockwise direction, viewing Figure 1, and as the jaw-opening rotates about the object 6, in a clockwise direction, spring 30 causes the movable jaw faces 33 and 34 to move toward the facets 35 and 36 of the work. It will be obvious that when any one 10 facet of the object comes into alignment with any gripping face of the wrench, all faces will align themselves. As alignment occurs, jaw 12 15 automatically moves upwardly into Figure 1 full line position, this being the only position into which the jaw can move because it is limited in motion and position by the action of ratchet teeth 26-27, links 20 and pins 21, 24 and 24', and by 20 coacting flat surfaces 15-28 above and below the toothed portions 26-27.

In the position just described the object is engaged along the total length of three of its six facets, and the movable jaw 12 cannot further 25 decrease the jaw opening 37, neither can it increase the latter, due to the pitch and shape of the ratchet teeth 26-27 and the pressure of work and jaw each against the other as the stock is rotated further in a clockwise direction. 30 The object may be rotated any number of full turns or a fraction of a turn in the manner previously described. However if the wrench handle is swung to the right or in a clockwise direction, the pressure just referred to is released, 35 and the teeth 26-27 become disengaged. Continued rotation of the wrench in this direction causes the movable jaw to swing outward and downward with respect to the movable jaw supporting member to allow free rotation of the jaw 40 opening 37 around the work. It will be obvious that with each free 60° rotation of the gripping jaws with respect to the work, one complete reciprocal movement of the movable jaw will take place, thus allowing a new gripping of the work, if desired. At any time during ratchet or gripping stroke, a movement of the wrench handle to the right will release movable jaw 12 from its locked engagement with the member 11, and further compression of spring 30 will allow disengagement of the wrench from the object, from 45 any position desired.

From the foregoing it will be noted that the inclination of the flat opposing edge faces 15 and 28, is such that the partial gripping face 34 of the movable jaw 12 will always be parallel to the gripping face 7 of the fixed jaw or head 2, and the inclination of gripping face 33 of movable jaw 12 will always be parallel to the jaw face 4, regardless of the extent to which the jaw supporting member 11 has been adjusted through the medium of circular nut 18. It will also be noted that downward pressure of the work against the partial gripping face 34 causes the movable jaw during the unlatching stroke of the wrench to 50 pivot slightly about the pins 24-24'.

Having thus described my invention what I claim is:

1. An open-end wrench comprising a body portion terminating at its outer end in a fixed jaw portion and at its inner end in a handle, the inner face of the fixed jaw having two fixed flat jaw faces immovably disposed at an angle of 60° to each other to receive two facets of a hexagonal work piece engaged by the wrench, said body formed with a longitudinal recess, a jaw support-

ing member slidably mounted in said recess, a movable jaw pivotally supported by said jaw supporting member, said movable jaw having two flat faces immovably disposed with respect to each other at an angle of 120° and adapted to receive two more facets of the work piece, said movable jaw and said movable jaw supporting member having opposing ratchet teeth, whereby said teeth on said movable jaw may be swung into and out of engagement with the teeth on said jaw supporting member, means for normally forcing said ratchet teeth into engagement with each other and the gripping faces of the movable jaw toward the gripping faces of the fixed jaw, said jaw faces of the movable jaw coacting with the jaw faces of the fixed jaw to engage the entire length of three facets of the hexagonal work piece, for the purpose of transmitting torque to said work when the wrench is turned in one direction, the movable jaw being automatically pivoted about its pivot by the pressure of the work to disengage the ratchet teeth and permit free ratcheting of the wrench about the work when the wrench is rotated in a counterdirection.

2. An open-end wrench comprising a body portion terminating at its outer end in a fixed jaw portion and at its inner end in a handle, the inner face of the fixed jaw having two fixed flat jaw faces immovably disposed at an angle of 60° to each other to receive two facets of a hexagonal work piece engaged by the wrench, said body formed with a longitudinal recess, a jaw supporting member slidably mounted in said recess, a movable jaw pivotally supported by said jaw supporting member, said movable jaw having two flat jaw faces immovably disposed with respect to each other at an angle of 120° and adapted to receive two more facets of the work piece, said movable jaw and said movable jaw supporting member having opposing ratchet teeth, whereby said teeth on said movable jaw may be swung into and out of engagement with the teeth on said jaw supporting member, means for normally forcing said ratchet teeth into engagement with each other and the gripping faces of the movable jaw toward the gripping faces of the fixed jaw, said jaw faces of the movable jaw coacting with the jaw faces of the fixed jaw to engage the entire length of three facets of the hexagonal work piece, for the purpose of transmitting clockwise torque to said work when the wrench is turned in one direction, the movable jaw being adapted to be automatically pivoted about its pivot by the

pressure of the work to disengage the ratchet teeth and permit free ratcheting of the wrench about the work when the wrench is rotated in a counter or reverse direction and manually operative means for slidably moving and controlling said movable jaw supporting member in said recess.

3. An open-end wrench comprising a body portion terminating at its outer end in a fixed jaw and at its other end in a handle, the fixed jaw having two fixed flat jaw faces inwardly disposed at an angle of approximately 60° to each other to receive two facets of a hexagonal work piece engaged by the wrench, said fixed jaw having a third flat face connecting said two fixed flat faces, a movable jaw supporting member slidably connected to said body portion, a movable jaw connected to said supporting member, said movable jaw and said jaw supporting member having coacting toothed portions, a spring normally urging the said toothed portions into mesh, said movable jaw having two flat faces of unequal dimensions immovably disposed with respect to each other at an angle of approximately 120° and adapted to receive two additional facets of the work piece, the larger of said last mentioned two flat faces on the movable jaw being parallel to one of the first mentioned two faces of the fixed jaw and the smaller of said last mentioned two flat faces of the movable jaw being parallel with the said third flat jaw face of said fixed jaw, and means for sliding said movable jaw supporting member relative to said wrench body without disturbing the aforesaid angularity of the flat faces of the movable jaw with respect to the flat faces of the fixed jaw.
